(57) **CLAIM**

The ornamental design for a dinosaur musical pounding toy, as shown and described.

DESCRIPTION

FIG. 1 is a front elevation view of the dinosaur musical pounding toy, showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a top-left perspective view thereof; and

FIG. 8 is a bottom-right perspective view thereof; and,

FIG. 9 is an enlarged view of the area labeled 9 in FIG. 8. The broken lines show portions of the dinosaur musical pounding toy that forms no part of the claimed design.

1 Claim, 9 Drawing Sheets
